US0D1010230S

(12) **United States Design Patent** (10) **Patent No.:** **US D1,010,230 S**
(45) **Date of Patent:** **** Jan. 2, 2024**

(54) **ARTIFICIAL LASH EXTENSION**

(71) Applicant: **Lashify, Inc.**, North Hollywood, CA (US)

(72) Inventor: **Sahara Lotti**, North Hollywood, CA (US)

(73) Assignee: **Lashify, Inc.**, North Hollywood, CA (US)

(**) Term: **15 Years**

(21) Appl. No.: **29/897,326**

(22) Filed: **Jul. 13, 2023**

Related U.S. Application Data

(63) Continuation of application No. 29/881,074, filed on Dec. 27, 2022.

(51) **LOC (14) Cl.** **28-04**

(52) **U.S. Cl.**

USPC **D28/92**

(58) **Field of Classification Search**

USPC D28/92, 93, 99

CPC A41G 5/02

See application file for complete search history.

(57) **CLAIM**

The ornamental design for an artificial lash extension, as shown and described.

DESCRIPTION

FIG. 1 is a top left perspective view of an artificial lash extension in accordance with the claimed design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines consisting of evenly spaced lines in the figures show portions of the artificial lash extension that form no part of the claimed design.

1 Claim, 4 Drawing Sheets
